DESIGN FOR A CHEST OF DRAWERS

William Millington, Grand Rapids, Mich., assignor
to Baker Furniture Factories, Inc., Grand
Rapids, Mich., a corporation of Michigan

Application January 31, 1934, Serial No. 50,569

Term of patent 3½ years

To all whom it may concern:

Be it known that I, WILLIAM MILLINGTON, a citizen of the United States, residing at 519 Gladstone, S. E., Grand Rapids, in the county of Kent and State of Michigan, have invented a new, original, and ornamental Design for a Chest of Drawers, of which the following is a specification, reference being had to the accompanying drawing, forming a part thereof, in which:

Figure 1 is a front elevational view of the chest of drawers, the essential or dominating features of the design being shown in full lines

and comprising the understructure having the curved surfaces as indicated and the superstructure which is recessed as indicated with respect to the understructure, the top, the legs and the several drawers together with their knobs or pulls being shown in dotted lines and indicating non-essential features of the design; and Figure 2 is an end elevational view thereof.

I claim:

The ornamental design for a chest of drawers as shown and described.

WILLIAM MILLINGTON.
